[57] CLAIM

The ornamental design for an orthopedic pillow, as
shown and described.

DESCRIPTION

FIG. 1 is an isometric view of an orthopedic pillow
showing my new design;

FIG. 2 is a top plan view, the bottom view being a
mirror image thereof;

FIG. 3 is a left end elevational view, the right end eleva-
tional view being a mirror image thereof;

FIG. 4 is a front elevational view; and

FIG. 5 is a rear elevational view thereof of FIG. 1.
